UNITED STATES PATENT OFFICE.

CORTLAND W. DAVIS, OF CHICAGO, ILLINOIS, ASSIGNOR TO THE MANTLE LAMP COMPANY OF AMERICA, OF CHICAGO, ILLINOIS, A CORPORATION OF ILLINOIS.

INVERTED INCANDESCENT MANTLE.

1,283,691.

Specification of Letters Patent.

Patented Nov. 5, 1918.

Application filed December 18, 1914. Serial No. 877,983.

To all whom it may concern:

Be it known that I, CORTLAND W. DAVIS, a citizen of the United States, residing at Chicago, in the county of Cook and State 5 of Illinois, have invented certain new and useful Improvements in Inverted Incandescent Mantles; and I do hereby declare the following to be a full, clear, and exact description of the invention, such as will enable others skilled in the art to which it 10 pertains to make and use the same.

This is an improvement in the production of incandescent structures or mantles for lighting purposes, and especially for burners of the inverted type. The invention relates more particularly to improved means for forming the cellulose structures of the mantle.

In inverted mantles it is desirable that the 20 lower end thereof shall be symmetrical and preferably semi-spherical in form to give a maximum efficiency in light. The well known Welsbach process of making mantles of this character, consists in impregnating 25 a structure of fibrous cellulose with solution of refractory earths, then igniting the fibrous structure and thereafter shaping the resulting refractory earth structure over a suitable flame. The dimensions of the finished structure 30 are generally about 50% of the impregnated cellulose structure and this finished structure is very similar in shape to the cellulose structure. It is desirable, therefore, to produce a cellulose structure of a form 35 and size which will result in a desired shape in the finished article.

The usual method of forming the cellulose structure for inverted mantles has been to attach one end of a tubular knitted fabric 40 to a suitable carrier or support, such as a lava collar, and to close the other, or lower, end of the fabric. Various means have been employed to close this lower end. One manner has been to close the lower end of the 45 tubular knitted structure by drawing the edges toward the center and either bunching and tying with a string, or passing a string through the loops of the knitting and drawing the loop string together. In either 50 case the fabric is bunched together around the center and is very objectionable, not infrequently increasing the weight of the material at the center to such an extent as to result in sagging out of symmetrical form, 55 and weakening the material of the mantle. Moreover, the end of an inverted mantle is

the point from which the maximum light can be obtained. The bunching of the material at this point reduces the efficiency of the mantle. Various methods of goring have 60 been employed to obviate the foregoing objections, but when sufficient goring has been done to produce a symmetrical closed end, the large number of seams found necessary, 65 become objectionable. It has also been proposed to close the end of this tubular knitted structure by sewing into it a flat elliptical piece of the same knitted structure, the shape 70 of the ellipse being designed to neutralize the unequal, longitudinal and transverse shrinkage of the knitting in the impregnated fabric when burned, and to thereby produce a section practically circular in form at the lower end of the mantle, after the mantle material shall have been shrunk by the burning 75 of the fibrous structure. This method, however, involves mechanical difficulties and requires skill to properly sew the elliptical section to the tubular section. Difficulty is encountered also, in proportioning the axes 80 of the ellipse so as to take care of all the conditions that vary the shrinkage of the fabric.

Prior to this invention it has never been feasible in constructing inverted mantles, to 85 sew a circular piece of fabric to a tubular knitted fabric in forming the end of an inverted mantle, because of the unequal shrinkage of the fabrics generally used in the end portion.

This invention retains the advantageous 90 features of the former methods, and especially that method which attaches one piece of fabric to another by a single circular seam, and at the same time eliminates the 95 disadvantages of the prior methods of producing mantles, wherein an elliptical section is sewed to the bottom of a tubular section.

This invention comprises the production 100 of an incandescent inverted mantle having a substantially cylindrical or tubular body section, the upper end of which is suitably secured to a carrier whereby the mantle may be supported from a burner. This tubular 105 body section is preferably made from knitted fabric, as is customary. The lower end of this tubular body, however, is closed by sewing a circular piece of fabric at substantially right angles to the tubular body section, 110 the essential feature of the invention residing in the provision of this closing disk

from a fabric which will shrink uniformly in all directions when the fibrous structure of the mantle is burned.

The shrinkage of the knitted fabric from 5 which the tubular body section may be made is unequal in the directions of length and width, and should the lower circular ends be made from the same material as the tubular section, it would result in a finished mantle with a distorted lower end, due to the unequal distribution of the threads resulting from the knitting of the fabric.

Figure 1 is a perspective view of a section of tubular fabric.

15 Fig. 2 is a detail view, greatly enlarged, of a section of the fabric of Fig. 1, shown knitted.

Fig. 3 is a plan view of a circular section of fabric.

20 Fig. 4 is an enlarged plan view of woven fabric of Fig. 3.

Fig. 5 is an enlarged plan view of another embodiment of woven fabric.

Fig. 6 is a side elevation of a mantle.

25 To produce the lower end for a mantle which is symmetrical in shape and which will give the maximum efficiency in light, I have provided an end member 1 circular in shape and of different material from the 30 tubular member 2, when constructed of knitted material, whereby the tubular and end members will shrink differently during the burning of the mantle, resulting in an end substantially parabolic in form and free 35 from thickened material except at the sides of the mantle. One means of accomplishing this result resides in making the tubular member of knitted fabric 3, as heretofore, and the circular end member shown in Fig. 40 3, may be of woven fabric, such as 4 in Fig. 4, or 4^a, as in Fig. 5. The end member 1 may be secured to the tubular member 2 by any suitable means, such as by sewing the parts together, as indicated by the 45 seam 5. This seam may be a single, circular seam. It is obvious that the tubular member 2 may be formed of the material of Fig. 5, and the member 1 formed of the material of Fig. 4, or the tubular member 2 and the 50 end member 1 may be formed of the same material as either 4 or 5. However, it is preferred to construct the substantially circular end member of Fig. 3 from the material of Figs. 4 or 5, and such woven material is preferably constructed so that it is 55 substantially the same number of cords or threads to the inch measured on any two axes at right angles to each other.

The resulting mantle, therefore, is composed of a plurality of parts, the fibrous cellulose structure of which may be of different materials, producing a substantially symmetrical mantle after shrinkage.

Having thus described my invention, what I claim as new and desire to secure by Letters Patent is:

1. An inverted incandescent mantle comprising a tubular body portion of fabric of unequal longitudinal and transverse shrinkages and a closed end portion made from 70 fabric of substantially the same number of threads to a given space measured on any two axes at right angles to each other whereby the fabric is of substantially equal longitudinal and transverse shrinkages. 75

2. A cellulose structure for an inverted incandescent mantle composed of a tubular body portion and a circular end portion, said end portion being attached to said tubular body portion, the fabric in said end portion being constructed of woven fabric so that in the incinerating process of treating the mantle, the shrinkage of said end portion is substantially equal longitudinally 80 and transversely. 85

3. An inverted mantle formed from a tubular knitted member and a circular end member of woven material united to the tubular member. 85

4. An inverted mantle having a tubular 90 body of knitted fabric, the major portion of its threads running lengthwise of the tube, and an end member formed from a single piece of woven material the threads of which are substantially at right angles 95 to each other.

5. An inverted mantle having a tubular body of knitted fabric, the major portion of its threads running lengthwise of the tube, and an end member formed from a circular 100 piece of woven material, said woven material being composed of threads having substantially the same number of threads to a given space measured on any two axes at right angles to each other. 105

6. A mantle structure including a cylindrical body portion and a closure for said body portion composed of crossed rows of parallel threads.

7. A mantle structure including a cylindrical body portion and a closure for said body portion composed of crossed rows of evenly spaced parallel threads. 110

8. A fabric mantle, having a cylindrical body section, and a closure for one end of 115 said body section, said closure having threads which are so laid that there are equal lengths of thread across similar dimensions of the closure.

In testimony whereof, I affix my signature, in presence of two witnesses. 120
